MINING MACHINE

Morris P. Holmes, Claremont, N. H., assignor to
 Sullivan Machinery Company, a corporation
 of Massachusetts

Application February 27, 1933, Serial No. 658,801

30 Claims. (Cl. 262—30)

This invention relates to mining machines, and more particularly to an improved adjustable kerf cutting mechanism for a coal mining machine.

An object of this invention is to provide an improved mining machine. Another object is to provide an improved adjustable kerf cutting mechanism for a mining machine. A further object is to provide an improved adjustable kerf cutting mechanism for a coal mining machine of the flexibly fed, continuous cutter type. Yet another object is to provide an improved mining machine of the room and pillar type having improved adjustable kerf cutting mechanism and improved means for adjusting and driving the kerf cutting mechanism. A further object is to provide a room and pillar mining machine of the adjustable cutter type of an extremely simplified and inexpensive construction. These and other objects and advantages of the invention will, however, hereinafter more fully appear.

In the accompanying drawings there is shown for purposes of illustration one form which the invention may assume in practice.

In these drawings,—

Fig. 1 is a plan view of the improved mining machine.

Fig. 2 is a side elevational view of the mining machine shown in Fig. 1.

Fig. 3 is a rear end elevational view of the mining machine shown in Figs. 1 and 2.

Fig. 4 is an enlarged central longitudinally extending vertical sectional view taken substantially on line 4—4 of Fig. 1, with parts shown in elevation to facilitate illustration.

Fig. 5 is a horizontal sectional view taken substantially on line 5—5 of Fig. 4.

In this illustrative construction the improved adjustable kerf cutting mechanism is shown embodied in a coal mining machine of the flexibly fed, continuous cutter, room and pillar type, although it will be evident that the improved cutting mechanism may be embodied in mining machines of various other types. The mining machine disclosed herein comprises a machine frame 1 having a floor plate 2 upon which the machine is adapted to rest and slide in any direction over the mine floor. The machine frame comprises a front frame section 3 housing the driving motor and a rear frame section 4 housing the transmission means for driving the kerf cutting mechanism and carrying the machine feeding mechanism. The frame section 3 constitutes the motor casing. Supported on the machine frame is the improved adjustable kerf cutting mechanism generally designated 5 having

improved adjusting means 6 and improved cutter driving means 7. The kerf cutting mechanism includes an elongated horizontally extending cutter bar 8 mounted in superimposed relation on the machine frame and having mounted on its margin, for circulation thereabout, a cutter bit carrying cutter chain 9. The machine may be fed in various manners and is herein fed over the mine floor during the cutting operation by flexible feeding means comprising feed operating and controlling drums respectively designated 10 and 11 and cooperating with feed cables 12 and 13, respectively. Arranged at the opposite front corners of the machine frame are guide sheaves 14, 15, while arranged at the opposite sides of the machine in advance of the feed operating and controlling drums are guide sheaves 15 and 16. Arranged at the opposite rear corners of the machine frame are sets of guide sheaves 17 and 18. The feeding and controlling cables may be extended from the feed operating and controlling drums in any preferred direction about the guide sheaves in the manner well understood by those skilled in the art. During cutting from right to left in accordance with the room and pillar system, the feed cable is extended from the feed drum 10 about the front guide sheave 14 at the advancing side of the machine and laterally along the coal face to a suitable anchor located at the left hand rib, while the controlling cable 13 is extended around the guide sheave 16 and the guide sheave 18 at the rear corner of the machine and then rearwardly to a suitable anchor located at the right hand rib. The machine is then sumped in and fed transversely across the coal face. During cutting from left to right, the feed cables are arranged in an opposite manner and the cutter chain is of course reversed.

Now referring to the improved adjustable kerf cutting mechanism 5, it will be noted that the motor housed within the frame section 3 is of the horizontal type having its power shaft extending longitudinally of the machine, and is herein preferably of the reversible electric type. Fixed to the rear end of the motor power shaft is a spur motor pinion 20 meshing with a spur gear 21 journaled for rotation about an axis parallel with and above the power shaft axis on a stub shaft 22 suitably supported within the frame section 4. Rotatable with and driven by the spur gear 21 is a bevel pinion 23 meshing with a large bevel gear 24 mounted for rotation about a vertical axis with its hub 25 keyed to a vertical shaft 26. The shaft 26 is suitably journaled within the frame section 4 and drives through worm gearing 27, in the

manner described in my copending application, Ser. No. 658,803, filed Feb. 27, 1933, the feed operating and controlling drums 10 and 11. Supported on the hub of the bevel gear is a bearing sleeve 28 on which there is rotatably mounted a drive sleeve 29 having clutch teeth 30 connectible by a sliding clutch element 31 in interlocking relation with the bevel gear for driving thereby. The clutch element 31 is slidably mounted on the 5 vertical shaft 26 and is operated by a clutch shipper sleeve 32 also slidably mounted on the shaft and having depending ears 33 connected to a pivoted shipper member 34. This shipper member is fixed to a transversely extending operating 10 rod 35 having at the advancing side of the machine an operating member 36. The bearing 28 and sleeve 29 are held against vertical displacement by a retaining member 37 overlying the bearing and sleeve and fixed by a bolt 38 to the 15 vertical shaft 26 in the manner shown in Fig. 4. Arranged between the sleeve 29 and the cutter chain is an extensible driving connection so that the cutter chain may be driven irrespective of the 20 adjusted position thereof with respect to the machine frame, and this extensible driving connection herein comprises lateral lugs 39 formed on the drive sleeve 29 and traversed by openings 40 receiving pivot pins or bolts 41 to which are pivotally connected at 42 driving arms 43, herein 25 three in number, in turn horizontally connected, as by pins or bolts 44 at their outer extremities, to cooperating driving arms 45. The inner adjacent ends of the arms 45 project between lateral ears on the lower arms 43 thereby forming a very 30 rigid construction with little tendency to distortion. The inner ends of the upper driving arms 45 are pivotally connected by pins or bolts 46 mounted in bores 47 formed within lateral lugs 48 integral with an upper drive sleeve 49. The drive 35 sleeve 49 is keyed at 50 to a chain sprocket 51 which engages and drives, in the usual manner, the cutter chain 9. The cutter chain drive sprocket is journaled in bearing sleeves 52 mounted within the top and bottom plates 53 and 54, 40 respectively, of the cutter bar 8. Formed integral with the cutter bar and projecting upwardly and shrouding the rearward portion of the cutter chain is a guard flange 55, this guard flange encircling the rearward portion of the cutter chain 45 and extending longitudinally in parallel relation 50 along the opposite sides of a cutter bar supporting frame 56. This cutter bar supporting frame has formed thereon integral guide elements 57 extending vertically at opposite sides of the cutter 55 supporting frame and having formed therein vertical guideways 58 engaging vertical guides 59 integral with the machine frame at the opposite sides of the machine. The improved mechanism for adjusting the elevation of the cutter bar relative to the machine frame, generally designated 60 at 6, is arranged at the forward end of the machine frame and the vertical guiding means for the cutter supporting frame are arranged longitudinally of the machine between the adjusting means 6 and the cutter driving means at the rear 65 end of the machine frame.

The improved means for adjusting the cutter bar in a vertical direction into different parallel cutting positions relative to the machine frame 70 comprises a large hand wheel 61 disposed between the cutter supporting frame and the machine frame and operable from either side of the machine. This hand wheel is keyed at 62 to the lower end of a tubular element 63, the latter having 75 formed thereon at its upper end an adjusting

nut 64. This adjusting nut is threadedly connected to an adjusting screw 65 engaging the upper plate of the cutter bar and fixed against rotative movement relative thereto, the screw having a squared portion 66 fitting a square socket in the upper cutter bar plate. Secured, as by bolts 67, to the lower plate of the cutter bar is a tubular element 68 which surrounds and houses the tubular element 63, the element 63 telescoping within the element 68 when the parts are in the position shown in Fig. 4. The lower end of the tubular element 63 is mounted in a bearing 69 supported within a bearing retaining element 70 secured to the top of the frame section 3. It will thus be seen that when the hand wheel 61 is manually rotated, the nut 64 rotates therewith, and as a result, the adjusting screw 65 moves axially in a vertical direction to effect vertical adjustment of the cutter bar, the cutter bar being guided during such adjustment by the guideways 58 cooperating with the vertical guides 59. During vertical adjustment of the cutter bar, a driving relation between the drive sleeve 29 and the sprocket driving sleeve 49 is constantly maintained by the hinged drive arms 43, 45, the drive arms swinging about 80 their hinged connections as the sprocket driving sleeve 49 moves upwardly with the cutter bar. 85

Although the hand wheel 61 is operated manually, it is clearly evident that if desired the same may be driven by an independent motor or 90 through suitable transmission connections by the motor of the machine. 95

As the operation of a room and pillar machine is well known to those skilled in the art, a more detailed description of the mode of operation of the machine is considered unnecessary. If it is desired to adjust the plane of operation of the cutter bar with respect to the mine floor, this 100 may be accomplished simply by rotating the hand wheel to operate the adjusting screw mechanism. 105

As a result of this invention, it will be noted that an improved adjustable kerf cutting mechanism is provided having improved transmission means whereby a constant drive is maintained between the parts relatively movable during adjustment of the kerf cutter and in a simplified manner. It will further be noted that an improved adjustable kerf cutting mechanism is provided for a mining machine of the room and pillar type and having improved adjusting mechanism, and improved mechanism for driving the kerf cutter, both the adjusting means and the cutter driving means being of an extremely simple design having relatively few and inexpensive moving parts which may be manufactured and replaced at a minimum of expense. These and other uses and advantages of the improved mining machine will be clearly apparent to those skilled in the art. 110 115 120 125 130

While there is in this application specifically described one form which the invention may assume in practice, it will be understood that this form of the same is shown for purposes of illustration and that the invention may be modified and embodied in various other forms without departing from its spirit or the scope of the appended claims. 135

What I claim as new and desire to secure by Letters Patent is:

1. In a mining machine, a machine frame 145 adapted to rest upon and slide in any direction over the mine floor, a horizontal kerf cutter superimposed on said machine frame and projecting forwardly of, and in parallelism with the major dimension of, said frame and with the 150

- rearward portion of said cutter overlying the rearward portion of said frame and adjustable into parallel cutting positions relative thereto, mechanism disposed between said kerf cutter and said machine frame for adjusting said kerf cutter as aforesaid, and motor operated mechanism for driving said kerf cutter irrespective of its adjusted position relative to said frame.

2. In a mining machine, a machine frame adapted to rest upon and slide in any direction over the mine floor, a horizontal kerf cutter superimposed on said machine frame and projecting forwardly of, and in parallelism with the major dimension of, said frame and with the rearward portion of said cutter overlying the rearward portion of said frame and adjustable into parallel cutting positions relative thereto, mechanism disposed between said kerf cutter and said machine frame for adjusting said kerf cutter as aforesaid, and motor operated mechanism for driving said kerf cutter irrespective of its adjusted position relative to said frame, said adjusting mechanism arranged adjacent the forward end of the machine frame in advance of said driving mechanism.

3. In a mining machine, a machine frame, a horizontal kerf cutter superimposed on said machine frame and overlying the same and adjustable into parallel cutting positions relative thereto, mechanism disposed between said kerf cutter and said machine frame for adjusting said kerf cutter as aforesaid, and motor operated mechanism for driving said kerf cutter irrespective of its adjusted position relative to said frame, said adjusting mechanism arranged adjacent the forward end of the machine frame and said driving mechanism adjacent the rearward end thereof.

4. In a mining machine, a machine frame, a horizontal kerf cutter mounted in superimposed, overlying relation on said frame, a frame overlying said machine frame and supporting said kerf cutter and said cutter supporting frame having depending vertical guideways, upstanding guides projecting above the top of said frame on the opposite sides of said machine frame and cooperating with said guideways, and mechanism arranged between the top of said machine frame and said cutter supporting frame and disposed adjacent the forward end of the machine frame in advance of said guideways for elevating said kerf cutter.

5. In a mining machine, a machine frame, a horizontal kerf cutter mounted in superimposed overlying relation on said frame, a frame supporting said kerf cutter and having depending vertical guideways, upstanding guides on the opposite sides of said machine frame and cooperating with said guideways, mechanism arranged between said machine frame and said cutter supporting frame and disposed adjacent the forward end of the machine frame in advance of said guideways for elevating said kerf cutter, and motor operated mechanism arranged on said machine frame at the rear of said guideways for driving said kerf cutter.

6. In a mining machine, a machine frame, a kerf cutter mounted on said frame for bodily adjustment into parallel cutting positions relative thereto, a motor carried by said frame and relative to which said kerf cutter is adjustable, and driving connections between said motor and said kerf cutter operative irrespective of the adjusted position of said kerf cutter relative thereto and including relatively pivoted driving elements hinged together and interposed between the top of

of said frame and said kerf cutter and rotatable during kerf cutter drive about aligned axes, said elements having relative pivotal movement during adjustment of said kerf cutter.

7. In a mining machine, a machine frame, a kerf cutter mounted on said frame for bodily adjustment into parallel cutting positions relative thereto, a motor carried by said frame and relative to which said kerf cutter is adjustable, and driving connections between said motor and said kerf cutter operative irrespective of the adjusted position of said kerf cutter relative thereto and including relatively pivoted driving arms hinged together and interposed between the top of said frame and said kerf cutter and rotatable during kerf cutter drive about axes perpendicular to the parallel kerf cutting portions of the bar, said elements having relative pivotal movement during adjustment of said kerf cutter.

8. In a mining machine, a machine frame, a kerf cutter mounted on said frame for bodily adjustment into parallel cutting positions relative thereto, a motor carried by said frame and relative to which said kerf cutter is adjustable, and driving connections between said motor and said kerf cutter operative irrespective of the adjusted position of said kerf cutter relative thereto and including hingedly connected drive arms and rotatable bodily about aligned axes during kerf cutter drive interposed between the top of said frames and said kerf cutter.

9. In a mining machine, a machine frame, a kerf cutter mounted on said frame for bodily adjustment into parallel cutting positions relative thereto, a motor carried by said frame and relative to which said kerf cutter is adjustable, and driving connections between said motor and said kerf cutter operative irrespective of the adjusted position of said kerf cutter relative thereto and including hingedly connected drive arms interposed between the top of said frame and said kerf cutter, said arms folding inwardly toward one another during lowering of the kerf cutter.

10. In a mining machine, a machine frame, a kerf cutter mounted on said frame for bodily adjustment into parallel cutting positions relative thereto, a motor carried by said frame and relative to which said kerf cutter is adjustable, and driving connections between said motor and said kerf cutter operative irrespective of the adjusted position of said kerf cutter relative thereto including a driving element operatively connected to the motor and projecting above the top of said frame, a driving element operatively connected to the kerf cutter, and extensible hingedly connected elements operatively connecting said driving elements in driving relation and interposed between the top of said frame and said kerf cutter.

11. In a mining machine, a machine frame, a kerf cutter superimposed on said frame, a frame supporting said kerf cutter, said cutter supporting frame adjustable into different elevated positions relative to said machine frame to vary the elevation of said kerf cutter, mechanism for adjusting said cutter supporting frame relative to said machine frame as aforesaid, a motor carried by said machine frame, and driving connections between said motor and said kerf cutter operative irrespective of the adjusted positions of said kerf cutter relative to said machine frame and including an element journaled on said machine frame and projecting above the top of the latter, an element journaled on said cutter supporting frame, and extensible driving connections oper-

- atively connecting said elements and interposed between the top of said frame and said kerf cutter, said connections including transmission elements having relative swinging movement during adjustment of the kerf cutter.
12. In a mining machine, a machine frame, a kerf cutter superimposed on said frame, a frame supporting said kerf cutter, said cutter supporting frame adjustable into different elevated positions relative to said machine frame to vary the elevation of said kerf cutter, mechanism for adjusting said cutter supporting frame relative to said machine frame as aforesaid, a motor carried by said machine frame, and driving connections between said motor and said kerf cutter operative irrespective of the adjusted position of said kerf cutter relative to said machine frame and including an element journaled on said machine frame and projecting above the top of the latter, an element journaled on said cutter supporting frame, and extensible driving connections operatively connecting said elements, respectively, comprising articulated transmission elements interposed between the top of said frame and said kerf cutter, said elements assuming different angularly related positions during adjustment of the kerf cutter. 80
13. In a mining machine, a machine frame, a kerf cutter superimposed on said frame, a frame supporting said kerf cutter, said cutter supporting frame adjustable into different elevated positions relative to said machine frame to vary the elevation of said kerf cutter, mechanism for adjusting said cutter supporting frame relative to said machine frame as aforesaid, a motor carried by said machine frame, and driving connections between said motor and said kerf cutter operative irrespective of the adjusted position of said kerf cutter relative to said machine frame and including an element journaled on said machine frame and projecting above the top of the latter, an element journaled on said cutter supporting frame, and extensible driving connections operatively connecting said elements in driving relation and interposed between the top of said frame and said kerf cutter, said connections including hingedly connected arms pivotally connected to said elements, respectively. 85
14. In a mining machine, a machine frame, a kerf cutter superimposed on said frame, a frame supporting said kerf cutter, said cutter supporting frame adjustable into different elevated positions relative to said machine frame to vary the elevation of said kerf cutter, mechanism for adjusting said cutter supporting frame relative to said machine frame as aforesaid, a motor carried by said machine frame, and driving connections between said motor and said kerf cutter operative irrespective of the adjusted position of said kerf cutter relative to said machine frame and including an element journaled on said machine frame and projecting above the top of the latter, an element journaled on said cutter supporting frame, an extensible driving connections operatively connecting said elements comprising arms pivotally connected to said elements, respectively, and interposed between the top of said frame and said kerf cutter, said pivotally connected elements hinged together at their adjacent ends. 90
15. In a mining machine, a machine frame, a kerf cutter superimposed on said frame, a frame supporting said kerf cutter, said cutter supporting frame adjustable into different elevated positions relative to said machine frame to vary the elevation of said kerf cutter, mechanism for adjusting said cutter supporting frame relative to said machine frame as aforesaid, a motor carried by said machine frame, and driving connections between said motor and said kerf cutter operative irrespective of the the adjusted position of said kerf cutter relative to said machine frame and including an element journaled on said machine frame and projecting above the top of the latter, an element journaled on said cutter supporting frame, an extensible driving connections operatively connecting said elements comprising arms pivotally connected to said elements, respectively, and interposed between the top of said frame and said kerf cutter, said arms hinged together at their adjacent ends, said arms swinging upwardly and relative to each other during elevation of said kerf cutter and folding inwardly during lowering of said kerf cutter. 95
16. In a mining machine, a machine frame, a kerf cutter overlying and mounted in superposed relation on said machine frame and adjustable into parallel cutting positions relative thereto, a motor carried by the forward portion of the machine frame beneath said kerf cutter, and operative connections between said motor and kerf cutter including driving elements arranged adjacent the rearward end of said frame, and mechanism arranged above said motor and extending substantially vertically above the same between said machine frame and said kerf cutter for adjusting said kerf cutter as aforesaid. 100
17. In a mining machine, a machine frame, a kerf cutter mounted in superimposed relation on said machine frame and adjustable into parallel cutting positions relative thereto, a motor carried by the forward portion of the machine frame beneath said kerf cutter, and operative connections between said motor and kerf cutter including driving elements arranged adjacent the rearward end of said frame, and manually operable screw mechanism disposed above the motor and between said machine frame and said kerf cutter for adjusting said kerf cutter as aforesaid. 105
18. In a mining machine, a machine frame, a kerf cutter mounted in superimposed relation on said machine frame and adjustable into parallel cutting positions relative thereto, a motor carried by the forward portion of the machine frame beneath said kerf cutter, and operative connections between said motor and kerf cutter including driving elements arranged adjacent the rearward end of said frame, and manually operable screw mechanism disposed above the motor and between said machine frame and said kerf cutter for adjusting said kerf cutter as aforesaid, said screw mechanism including a manually rotatable hand wheel operable from either side of the machine. 110
19. In a mining machine, a frame, a kerf cutter overlying said frame and adjustable bodily into parallel cutting positions relative thereto, a motor carried by said frame, and extensible driving connections between said motor and kerf cutter including pivotally connected drive arms interposed between the top of said frame and the kerf cutter. 115
20. In a mining machine, a frame, a kerf cutter overlying said frame and adjustable bodily into parallel cutting positions relative thereto, a motor carried by said frame, and extensible driving connections between said motor and kerf cutter including a rotatable drive element on the kerf cutter and projecting below the bottom of the latter, a rotatable driving element on the frame 120
- 75

- and projecting above the top of the latter, and relatively pivoted elements connecting said drive elements in driving relation and interposed between said frame and kerf cutter.
- 5 21. In a mining machine, a machine frame, a horizontal kerf cutter arranged in superimposed, overlying relation on the top of said frame, a frame supporting said kerf cutter and having an upstanding guard flange encircling the rearward portion of the kerf cutter, mechanism interposed between the top of said machine frame and said cutter supporting frame for adjusting the kerf cutter into parallel horizontal cutting positions with respect to said machine frame, and motor operated mechanism for driving said kerf cutter irrespective of the adjusted position thereof relative to said machine frame. 80
- 10 22. In a mining machine, a machine frame, a horizontal kerf cutter arranged in superimposed, overlying relation on the top of said frame, a frame supporting said kerf cutter and having an upstanding guard flange encircling the rearward portion of the kerf cutter and also having depending guide means, upstanding guide means projecting upwardly from said machine frame and cooperating with said depending guide means, mechanism interposed between the top of said machine frame and the cutter supporting frame for adjusting the kerf cutter into parallel horizontal cutting positions with respect to the machine frame, and motor operated mechanism for driving said kerf cutter irrespective of the adjusted position thereof relative to said machine frame. 85
- 15 23. In a mining machine, a machine frame adapted to rest upon and slide in any direction over the mine floor, a horizontal kerf cutter superimposed on said machine frame and projecting forwardly in parallelism with the latter with the rearward portion of said cutter overlying the rearward portion of said frame and adjustable into parallel cutting positions relative to said frame, a motor carried by said frame and relative to which said kerf cutter is adjustable, and extensible driving connections between said motor and said kerf cutter operative irrespective of the adjusted position of said kerf cutter relative thereto. 90
- 20 24. In a mining machine, a machine frame adapted to rest upon and slide in any direction over the mine floor, a horizontal kerf cutter superimposed on said machine frame and projecting forwardly of, and in parallelism with, the latter with the rearward portion of said cutter overlying the rearward portion of said frame and adjustable into parallel cutting positions relative thereto, a motor carried by said frame and relative to which said kerf cutter is adjustable, and extensible driving connections between said motor and said kerf cutter operative irrespective of the adjusted position of said kerf cutter relative thereto including a driving element journaled on said machine frame and projecting above the top of the latter and an extensible connection between said element and the kerf cutter. 100
- 25 25. In a mining machine, a machine frame, a motor thereon, a horizontal kerf cutter superimposed on said machine frame and overlying the latter and adjustable into parallel cutting positions relative thereto and relative to said motor, mechanism disposed between said kerf cutter and said machine frame for adjusting said kerf cutter as aforesaid, and motor operated mechanism driven by said motor for driving said kerf cutter irrespective of its adjusted position relative to said machine frame. 105
- 30 26. In a mining machine, a machine frame, a horizontal kerf cutter superimposed on said machine frame and overlying the latter and adjustable into parallel cutting positions relative thereto, mechanism disposed between said kerf cutter and said machine frame for adjusting said kerf cutter as aforesaid and including a screw and nut mechanism interposed in the space between the top of said frame and the bottom of said kerf cutter, and motor operated mechanism having a driving motor disposed beneath said adjusting mechanism on said frame for driving said kerf cutter irrespective of its adjusted position relative to said frame. 110
- 35 27. In a mining machine, a machine frame, a horizontal kerf cutter superimposed on said machine frame and adjustable into parallel cutting positions relative thereto, mechanism disposed between said kerf cutter and said machine frame for adjusting said kerf cutter as aforesaid and including a screw and nut mechanism interposed in the space between the top of said frame and the bottom of said kerf cutter, and a relatively large hand wheel of a diameter substantially equal to the width of the machine frame for operating said screw and nut mechanism. 115
- 40 28. In a mining machine, a machine frame, a kerf cutter superimposed on said frame, a frame supporting said kerf cutter, said cutter supporting frame adjustable into different elevated positions relative to said machine frame to vary the elevation of said kerf cutter, mechanism for adjusting said cutter supporting frame relative to said machine frame as aforesaid, a motor carried by said machine frame, and driving connections between said motor and said kerf cutter operative irrespective of the adjusted position of said kerf cutter relative to said machine frame and including an element journaled on said machine frame, an element journaled on the cutter supporting frame, said cutter supporting frame having an annular recess surrounding said latter element and within which said element projects, and extensible driving connections operatively connecting said elements and including transmission elements having relative swinging movement during adjustment of the kerf cutter, the elements connected to said second mentioned element swinging within said recess when said cutter supporting frame is lowered into its lowermost position. 120
- 45 29. In a room and pillar mining machine, a machine frame adapted to rest upon and slide in any direction over the mine floor, a motor carried by said frame, feeding means driven by said motor including relatively rotatable flexible feed member engaging feeding members journaled on said frame for moving said frame laterally across the coal face during the cutting operation, a horizontal kerf cutter superimposed on said machine frame and overlying said motor and feeding mechanism, said kerf cutter adjustable into parallel cutting positions relative to the machine frame, mechanism disposed between said kerf cutter and said machine frame for adjusting said kerf cutter as aforesaid, and motor operated mechanism for driving said kerf cutter irrespective of its adjusted position relative to said machine frame. 125
- 50 30. In a room and pillar mining machine, a machine frame adapted to rest upon and slide in any direction over the mine floor, a motor carried by said frame, feeding means driven by said motor including relatively rotatable flexible feed member engaging feeding members journaled on said frame for moving said frame laterally across the coal face during the cutting operation, a horizontal kerf cutter superimposed on said machine frame and overlying said motor and feeding mechanism, said kerf cutter adjustable into parallel cutting positions relative to the machine frame, mechanism disposed between said kerf cutter and said machine frame for adjusting said kerf cutter as aforesaid, and motor operated mechanism for driving said kerf cutter irrespective of its adjusted position relative to said machine frame. 130
- 55 31. In a room and pillar mining machine, a machine frame adapted to rest upon and slide in any direction over the mine floor, a motor carried by said frame, feeding means driven by said motor including relatively rotatable flexible feed member engaging feeding members journaled on said frame for moving said frame laterally across the coal face during the cutting operation, a horizontal kerf cutter superimposed on said machine frame and overlying said motor and feeding mechanism, said kerf cutter adjustable into parallel cutting positions relative to the machine frame, mechanism disposed between said kerf cutter and said machine frame for adjusting said kerf cutter as aforesaid, and motor operated mechanism for driving said kerf cutter irrespective of its adjusted position relative to said machine frame. 135
- 60 32. In a room and pillar mining machine, a machine frame adapted to rest upon and slide in any direction over the mine floor, a motor carried by said frame, feeding means driven by said motor including relatively rotatable flexible feed member engaging feeding members journaled on said frame for moving said frame laterally across the coal face during the cutting operation, a horizontal kerf cutter superimposed on said machine frame and overlying said motor and feeding mechanism, said kerf cutter adjustable into parallel cutting positions relative to the machine frame, mechanism disposed between said kerf cutter and said machine frame for adjusting said kerf cutter as aforesaid, and motor operated mechanism for driving said kerf cutter irrespective of its adjusted position relative to said machine frame. 140
- 65 33. In a room and pillar mining machine, a machine frame adapted to rest upon and slide in any direction over the mine floor, a motor carried by said frame, feeding means driven by said motor including relatively rotatable flexible feed member engaging feeding members journaled on said frame for moving said frame laterally across the coal face during the cutting operation, a horizontal kerf cutter superimposed on said machine frame and overlying said motor and feeding mechanism, said kerf cutter adjustable into parallel cutting positions relative to the machine frame, mechanism disposed between said kerf cutter and said machine frame for adjusting said kerf cutter as aforesaid, and motor operated mechanism for driving said kerf cutter irrespective of its adjusted position relative to said machine frame. 145
- 70 34. In a room and pillar mining machine, a machine frame adapted to rest upon and slide in any direction over the mine floor, a motor carried by said frame, feeding means driven by said motor including relatively rotatable flexible feed member engaging feeding members journaled on said frame for moving said frame laterally across the coal face during the cutting operation, a horizontal kerf cutter superimposed on said machine frame and overlying said motor and feeding mechanism, said kerf cutter adjustable into parallel cutting positions relative to the machine frame, mechanism disposed between said kerf cutter and said machine frame for adjusting said kerf cutter as aforesaid, and motor operated mechanism for driving said kerf cutter irrespective of its adjusted position relative to said machine frame. 150

any direction over the mine floor, flexible feeding means including advance and receding flexible feeding portions for feeding said frame laterally across the coal face during the cutting operation, a rigid kerf cutter superimposed on and extending lengthwise of said frame, the rearward portion of said kerf cutter overlying the rearward portion of said frame, mechanism between the forward end of said frame and said kerf cutter

CERTIFICATE OF CORRECTION.

Patent No. 1,981,106.

November 20, 1934.

MORRIS P. HOLMES.

It is hereby certified that error appears in the printed specification of the above numbered patent requiring correction as follows: Page 3, lines 103, 104 and 105, claim 8, strike out the words " and rotatable bodily about alined axes during kerf cutter drive" and insert the same after "cutter" and before the comma in line 106, of said claim; and line 145, claim 11, for "positions" read position; page 4, lines 42 and 64, claims 13 and 14 respectively, for "an" read and; and line 88, claim 15, after "frame" insert a comma; and that the said Letters Patent should be read with these corrections therein that the same may conform to the record of the case in the Patent Office.

Signed and sealed this 19th day of February, A. D. 1935.

(Seal)

Leslie Frazer
Acting Commissioner of Patents.
